UNITED STATES PATENT OFFICE.

WALTER BRUCE WILLS, OF BALTIMORE, MARYLAND.

DESIGN FOR A DISPLAY EASEL.

Application filed July 15, 1925. Serial No. 14,103. Term of patent 3½ years.

To all whom it may concern:

Be it known that I, WALTER BRUCE WILLS, a citizen of the United States, residing at Baltimore city, State of Maryland, have invented a new, original, and ornamental Design for Display Easel, of which the following is a specification, reference being had to the accompanying drawing, forming part thereof.

Fig. 1 is a view in elevation of an easel showing my new design, and Fig. 2 is a view in side elevation thereof.

I claim:

The ornamental design for a display easel, as shown.

In testimony whereof I affix my signature.

WALTER BRUCE WILLS.
